(57) **CLAIM**

The ornamental design for a sink, as shown and described.

DESCRIPTION

In a preferred embodiment, the nature of this product is as a sink, in the form of a sink basin and sink basin and drawer assembly, primarily useful for washing kitchen items and other objects.

FIG. 1 is a right, top, front perspective view of a sink according to my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a left, top, front perspective view of a sink according to another embodiment of my new design, the views thereof being mirror images of the views shown in respective FIGS. 2-7.

The broken line representations in the figures are for the purpose of illustration only, and form no part of the claimed design.
